UNITED STATES PATENT OFFICE.

HENRY H. MURRAY, OF RIVERTON, NEW JERSEY, ASSIGNOR TO VICTOR TALKING MACHINE COMPANY, A CORPORATION OF NEW JERSEY.

MOTOR MOUNTING.

Application filed November 15, 1923. Serial No. 674,907.

My invention relates to mountings upon which motors are supported, and more particularly to that type or kind of mounting wherein the motor is yieldingly supported, 5 with a view of reducing or entirely eliminating motor noises which are frequently disturbing, distracting and altogether objectionable particularly when the motor is employed to operate a musical instrument. Motors for operating musical instruments, such as talking machines, generally operate comparatively quietly, so far as any audible sounds are concerned, but since certain parts of such motors usually rotate at relatively 15 high speeds there is generally some slight sound produced due to the engagement of the gearing therein and to vibration of the motor occasioned probably by some unbalanced portion of the rapidly moving parts. 20 But such motors are usually comparatively rigidly mounted and secured to a motor-board or to a partition or wall of the cabinet in which the motor is housed and these slight noises and the vibrations of the motor are 25 thus directly conducted or transmitted to a wall of a more or less sound-resonant chamber, where they are considerably amplified or augmented, often to such an extent as to divert attention from the musical selection being reproduced by a motor driven instrument.

The object of my invention is to provide a mounting for such a motor which will permit the motor as a whole to vibrate slightly, 35 while running, without transmitting those vibrations to any part of the cabinet structure or motor-board, and to confine those vibrations to the motor structure itself with the result that the vibration of the motor 40 may produce no audible sound.

A further object of my invention is to actually reduce the motor noises by supporting the motor structure upon resilient springs, so that the motor mechanism is 45 yieldingly or floatingly mounted with respect to the main support therefor and may vibrate, within narrow limits, without actual contact with any rigid relatively unyielding resonant structure.

50 A further object of my invention is to mount a motor of the character above referred to, so securely upon its support that it may not be substantially moved from its fixed position on the support or become displaced therefrom during shipment, and at

the same time to positively prevent any direct contact or engagement of the motor mechanism with any rigid part of the structure in or on which it may be mounted.

A further object is to sound-insulate the 60 support, which may be a motor-board, from the motor and from the rods by which the motor is mounted on the motor-board, and to sound-insulate the motor-frame from said rods and from said support so that there is 65 no continuous rigid metallic connection or contact between said parts.

A further object of my invention is to so mount the motor with respect to its support that the entire weight of the motor is carried and balanced by resilient springs under compression which is due only to the weight of the motor frame and the parts carried thereby, said motor when being operated being normally out of contact or engagement 75 with said support or any other object except said springs, so that it is free to vibrate and to move slightly in any direction unrestrained in any manner except by the resiliency of said springs on which it rests and 80 gravity.

Other objects of my invention will appear in the specification and claim below.

Referring now to the drawings, forming a part of this specification, and in which the same reference characters are employed throughout to designate the same parts, Figure 1 is a side elevational view of a talking machine motor secured to a motor-board of a talking machine cabinet, which board 85 is sectional on a vertical plane passing through the talking machine spindle, said motor being yieldingly or floatingly mounted on said board or support in accordance with 90 my invention. Fig. 2 is a plan view of the bottom side of the motor shown in Fig. 1 and of the three-point yielding mounting therefor.

Fig. 3 is a vertical sectional view on a somewhat larger scale than that of Figs. 1 100 and 2 of one of the yielding vibration-absorbing sound-insulating supports for a motor, all the parts being in vertical section except the central rod or bolt, which is shown in elevation; and

Fig. 4 is a side elevational view of the structure shown in Fig. 3.

In Figs. 1 and 2 there is shown a motor 1 which may be of any type or form so long as it comprises a rigid motor-frame 2, which is 110

usually of a rigid cast or assembled metal construction. On this motor-frame may be mounted the spring-barrel or other power element 3, the gearing 4, the spindle 5 and the governing mechanism 6. This motor 1 is shown as mounted on the support 7, which may be a motor-board or a partition or wall of a talking machine cabinet or any relatively rigid support for any motor, the noises of which it is desirable to reduce to a minimum. For convenience I will hereinafter in the detailed description refer to this support 7 as a motor-board.

In the particular structure shown in Figs. 15 1 and 2 this motor 1 is directly supported on compression springs 8, preferably three in number, the lower ends of said springs being supported by bolts or rods 9 passing through the motor-board or support and the 20 motor frame. The general arrangement and disposition of these three spring supports is plainly shown in Fig. 2.

These three spring supports are all alike and for a detailed description thereof reference will now be had to Figs. 3 and 4. The rod 9 is preferably a bolt or screw having on its upper end a head 10 and having its lower end provided with screw-threads 11 over which may be threaded a nut 12 and a 30 lock nut 13. The support or motor-board 7 is preferably provided with a cylindrical hole 14 passing vertically therethrough, into which is snugly fitted a bushing 15 of any suitable yielding non-metallic sound-insulating material such as soft rubber. The inside diameter of the bore of this bushing 15 is preferably substantially the same as the diameter of the rod or bolt 9 so that the said rod fits snugly in this soft yielding bushing. 40 Under the head 10 of the rod 9 I may provide a light steel washer 16 and between it and the upper side of the support on the motor-board 7, I provide a washer 17 which is also of yielding non-metallic sound-insulating material, such as felt. In this way the bolt or rod 9 is completely sound-insulated from the support 7, but is not rigidly mounted therein, the lower end of the bolt being slightly movable transversely, against 50 the resistance of the yielding resilient bushing 15.

The motor-frame 2 is provided with three holes 18 adapted to align with the three holes 14 in the support 7, and it is through 55 these holes that the bolts 9 freely pass.

Referring again to Fig. 3, hole 18 is preferably provided or lined with a bushing 19 of yielding non-metallic sound-insulating material, such as soft rubber, and is shown 60 as frictionally retained therein by fitting snugly into the hole 18. The bore or hole through this bushing 19 is preferably substantially larger than the diameter of the bolt 9 passing therethrough, so that the bolt 65 9 may normally be just out of contact with

the interior of the bushing 19. The lower end 20 of this bushing 19 preferably extends beyond or below the motor-frame 2 in the space between the bolt 9 and the upper end of the compression spring to prevent the 70 upper end of said spring from being slipped transversely into direct contact or engagement with the bolt 9. The lower end of the spring 8 preferably rests upon a steel bushing 21 projecting into the space between 75 the lower end of the spring 8 and the bolt 9 and having on its lower end a circular flange 22 adapted to rest squarely on the nut 12. Between the support 7 and the motor-frame 2 and preferably surrounding the bolt 9, I 80 may insert a pad, ring or washer 23 of yielding non-metallic sound-insulating material, such as felt, so that no actual contact or engagement of the motor-frame 2 with the support 7 is possible. Preferably this felt 85 washer 23 rests on or is secured to the side of the motor-frame 2 adjacent the support 7, but it may be secured to the support 7 and spaced from the motor-frame. The nut 12 is so adjusted that the upper surface of the 90 washer 23 is normally out of engagement with the under side of the support 7.

By reason of this construction the motor-frame and the parts carried thereby are supported on a plurality of compression springs 95 8. When the motor is running the motor-frame as a whole may freely move or vibrate slightly on these springs without communicating that motion to the rods 9 or to the support 7. The motor-frame may vibrate 100 in any direction without transmitting such motion to any part of the structure except to the springs 8. Because yielding non-metallic sound-insulating material is interposed between the bolt head 10 and the support 7; between the shank of the bolt 9 and the support 7; between the support 7 and the motor-frame 2; between the motor-frame 2 and the bolt 9; and between the upper ends 105 of the springs 8 and the bolts 9, there can 110 be no direct contact or engagement between the bolts 9 and the support 7 or between the bolts 9 and the motor-frame 2, or between the motor-frame and the support 7, and no vibration or movement of the motor 115 or sound produced by the operation of the motor is transmitted or conveyed by any solid sound-conductive part to the support or motor-board or to any wall or any partition of any chamber of a talking machine 120 structure.

As a result of this, any motor noises are substantially eliminated, and if such a motor is used in a talking machine structure there are no motor noises produced which will 125 reach the ear of one listening to the reproduction of sound from the talking machine.

It is to be understood that the nuts 12 are not for the purpose of compressing the felt washer 23 between the support 7 and the 130

motor-frame 2. They are for providing shoulders or projections on the bolts or rods 9 for supporting the lower ends of the springs 8 and for the purpose of adjusting 5 the felt washers 23 relatively close to, but out of actual contact with, the under side of the motor-board or support 7.

The springs 8 are compression springs, that is to say, the weight of the motor supported therein tends to compress these 10 springs as distinguished from elongating or extending them, said weight being balanced by the tension of the springs.

When the motor is properly positioned, 15 that is to say, so resting that the support 7 is substantially horizontal, there should be a free space between the felt washer 23 and the under side of the support so that there will be no actual contact between the motor-frame 2 and the parts carried thereby, and the support or motor-board 7 and the parts carried thereby. Under these conditions, 20 the rods or bolts 9 should also be just out of contact or engagement with the bore of the flexible bushings 19 so that there will be a clearance or slight space between them. When so constructed and positioned, the entire weight of the motor-frame 2 and the parts carried thereby will be carried and 25 balanced by the resilient springs 8 and the motor-frame and the motor mechanism mounted therein will be out of actual contact or engagement with the support 7 and the rods 9 or any other object and will be 30 free to move slightly or vibrate in any direction unrestrained by anything except the resiliency of the springs 8 upon which the weight of the motor is carried and gravity.

While I have described with considerable 35 particularity the exact structure illustrated in the drawings forming a part of this

specification, I do not wish to be construed as being limited strictly thereto, inasmuch as many slight changes might be made therein without departing from the spirit and scope of my invention as set forth in the appended claim.

Having thus described my invention, I claim and desire to protect by Letters Patent of the United States:

The combination with a motor-support and a motor comprising a rigid motor-frame, of a plurality of rigid rods mounted on said support and projecting therefrom, metallic compression springs supported at 55 their lower ends by said rods and surrounding but spaced from said rods and upon the upper ends of which said motor-frame rests and by which the weight of said motor is balanced, said frame being provided with a 60 plurality of openings through which said rods respectively pass, yielding, sound-insulating material between said rods and said support to prevent any actual contact of said rods with said support and to permit 65 said rods to yield slightly with respect to said support, and bushings of yielding, sound-insulating material fitted into said openings in said motor-frame, each bushing having a bore therethrough of a diameter 70 substantially larger than the diameter of the rod passing therethrough and projecting beyond said motor-frame into the space between a spring and a rod whereby said motor frame is free to slightly move and vibrate 75 in any direction with respect to said rods and with respect to said support unrestrained except by the resiliency of said springs and gravity.

In witness whereof, I have hereunto set 80 my hand this 13th day of November, 1923
HENRY H. MURRAY.
